METHOD OF AND APPARATUS FOR
SPINNINGWilliam Whitehead, Cumberland, Md., assignor
to Celanese Corporation of America, a corpora-
tion of Delaware

Application January 21, 1929. Serial No. 333,843

4 Claims. (Cl. 18—8)

This invention relates to method of and apparatus for the manufacture of artificial filaments, such as yarns, bristles and the like, and relates more particularly to those methods wherein a solution of a derivative of cellulose in a volatile solvent is extruded through orifices into a heated evaporative atmosphere, which methods are known as dry spinning methods.

An object of my invention is to obtain artificial filaments or yarns containing organic derivatives of cellulose that have more uniform lustre and other optical and physical properties than those previously made. A further object of my invention is to provide a process of and apparatus for the dry spinning of artificial filaments from solutions of derivatives of cellulose in volatile solvents, whereby the solution of the derivative of cellulose is heated near the temperature at which it is in equilibrium with the evaporative atmosphere prior to extrusion through the orifices of the jet or spinneret.

A further object of my invention is to provide a process of and apparatus for the dry spinning of artificial filaments from solutions of derivatives of cellulose in volatile solvents, wherein the temperature of the solution is maintained substantially uniform prior to extrusion through the orifices of a jet or spinneret. Other objects of my invention will appear from the following detailed description.

In a method heretofore employed for the dry spinning of artificial yarn from a solution of derivatives of cellulose and volatile solvents, such solution is forced by a pump, which is outside a spinning cabinet, into a spinning unit which comprises a spinning jet and sometimes a filter, which jet and filter are situated within the cabinet through which a heated evaporative gas flows. The filaments formed are passed through the evaporative atmosphere where the volatile solvent evaporates, and the dry filaments are wound on a textile machine.

The prior method does not produce yarns of perfectly uniform lustre, or uniform other optical or physical characteristics. I have found that this is due, among other factors, to the fact that the solution of derivatives of cellulose is not at sufficiently elevated temperature and is not of uniform temperatures just prior to its leaving the orifices of the spinning jet. I have found that in order to obtain lustrous filaments or yarns, elevated temperatures of the evaporative medium and of the spinning solutions are necessary, and the reduction of such temperatures lowers the lustre of the yarns produced. Further, if these

temperatures are lower, the physical strength of the yarns produced is somewhat lower, and the actual drying of the filaments or yarns is poor. Therefore, if these temperatures vary during the spinning process, filaments or yarns of varying lustre, strength and other optical or physical properties are produced.

In the method formerly employed, the spinning solution in the jet or spinneret is heated to some extent by the heated drying atmosphere that flows by it. However, this heating is not uniform, due to the fact that the convection currents in the spinning cabinet vary and thus cause different temperatures around the jet and around the filaments under formation. This non-uniform heating is also due to the fact that the drafts or differences in temperatures outside the cabinet cause the spinning solutions to have different temperatures prior to their entry into the spinning cabinet, and the amount of heat supplied to the spinning solution while in the cabinet prior to the extrusion through the orifices of the spinneret by heat exchange with the heated evaporative atmosphere, is not sufficiently great to impart uniform temperatures to the spinning solution.

I have found that if the spinning solution is positively heated by a suitable medium to a uniform temperature, which temperature is preferably near the temperature of the evaporative atmosphere in the vicinity of the mouth of the spinning jet, just prior to extrusion through the orifices of the jet, filaments or yarns of uniform lustre, strength, cross section and other optical and physical properties may be produced.

In accordance with my invention I prepare artificial filaments from solutions of organic derivatives of cellulose in a suitable volatile solvent by passing the same through chambers or other devices where they are positively heated by a suitable heating medium of uniform temperature, wherein the temperature of the spinning solution is raised to a point that is near the boiling point of the volatile solvent, just prior to their extrusion through the orifices of a spinning jet into a heated evaporative atmosphere. The filaments or yarns thus formed are then drawn off and wound onto a winding machine running at a uniform rate, which winding machine may also impart twist to the filament, if desired. The filaments or yarns thus formed are of a high and uniform lustre and have other desirable uniform optical and physical properties.

Any suitable artificial filaments or yarns may be produced by my invention. The filaments may be fine, say having deniers of less than 2 to 10

or more, to be used as such, or to be associated together to form yarns of various size. Heavier filaments having deniers of 20 to 500 or more may also be made to be used as artificial bristles 5 for brushes or artificial fur. Bands or ribbons may also be made by my invention to be used in making braids or as artificial straw.

Any suitable organic derivative of cellulose may be employed such as organic esters of cellulose 10 and cellulose ethers. Examples of organic esters of cellulose are cellulose acetate, cellulose formate, cellulose propionate and cellulose butyrate, while examples of cellulose ethers are ethyl cellulose, methyl cellulose and benzyl cellulose. Solutions of cellulose nitrate may also be spun in 15 this manner, and if desired the cellulose nitrate filaments or yarns may then be denitrated in any suitable manner.

Any suitable solvent may be employed examples 20 of which are acetone, mixtures of chloroform and ethyl alcohol or methyl alcohol, ethylene dichloride, methylene chloride and alcohol, or other suitable solvents or suitable mixtures of these, to which may be added suitable diluents, if desired.

The spinning solution may be heated in chambers while being conveyed to the mouth of the spinning jet. The pump that feeds the solution at uniform rate, the filter or candle, or the spinning jet may be placed in these chambers as well as the pipes connecting these various parts. While the device that immediately feeds the spinning jet should always be placed in such heating chamber, it is not absolutely necessary that either the pump or the filter should be placed in such chambers, although under some circumstances it is desirable that all of these parts be heated. Where solvents of comparatively high boiling points are employed, I prefer not to heat 35 the pump too high for obvious reasons.

The heating medium employed for heating the devices containing the spinning solution should produce uniform temperature and may be of any suitable character. I prefer to employ as a heating 40 medium liquids of high boiling points and reasonably low vapor pressure in order to avoid evaporation losses. Such liquids should preferably also have a high specific heat so that upon the loss of a given number of calories, little drop 45 of temperature is experienced. In order to avoid convection currents, the liquid should preferably be of high viscosity. An example of a liquid that combines all these properties is a heavy mineral lubricating oil. Other liquids such as water may 50 also be employed. However, the use of heated air or other gas is not excluded, and because of the comparatively uniform temperature of the drying evaporative gas of the spinning cabinet, this gas may also be employed, in which case the candles or heating devices for the spinning solution 55 may be placed in the exhaust lines of the heated evaporative atmosphere.

The heating medium may be circulated either by thermosyphonic action or by pumps or fans 60 from the chamber wherein it heats the spinning solution to another chamber where it is subjected to the action of heating elements such as steam coils, electrically heated elements, or by coils containing the hot evaporative atmosphere from the spinning jet, or these heating elements may be placed in the chamber wherein the spinning solution 65 is heated.

As stated, the temperature to which the spinning solution is elevated just prior to its extrusion through the orifices of a spinneret is prefer-

ably somewhat below the temperature of the drying evaporative atmosphere at that point. The temperature of the spinning solution in the jet should preferably not be raised above the boiling point of the solvents therein, since under these 80 conditions bubbles may be formed in the filaments issuing from the jet.

In order further to illustrate my invention reference is had to the accompanying drawing wherein

Figure 1 is a vertical cross section of a spinning unit provided with one form of means for carrying out my invention.

Figure 2 is a vertical cross section of a part of a spinning unit provided with another means for carrying out my invention.

Figure 3 is a vertical cross section of a part of a spinning unit provided with still another means for carrying out my invention.

Figure 4 is a vertical cross section of a part of a spinning unit having a restricted evaporative space provided with the means for heating the spinning solution shown in Figure 1.

Referring to Figure 1, the reference numeral 1 indicates the walls of a dry spinning unit, which 100 walls are preferably lagged with a suitable heat insulating material to prevent heat loss. While only one spinning unit is shown in the drawing, usually two, three, four or more are placed together in one cabinet. The spinning solution is 105 fed by the pipe to a pump 3 which supplies a practically uniform amount of spinning solution per unit of time to the pipe 4 which leads to a candle 5 that contains a filtering medium in order to filter out any trace of solid impurities that may 110 be present in the spinning solution. The spinning solution from the candle 5 passes to the metal cap or jet 6 having a number of holes or orifices of required size therein.

Upon extrusion of the spinning solution through 115 the orifices of the jet 6, the fine threads of spinning solution lose at least part of their volatile solvents as vapors, and assume the form of tough filaments or threads 7 of predetermined size. These filaments pass under the guide roller 8 120 around the rotating roller 9 and pass to any suitable winding device (not shown). If desired, this winding device may also twist the filaments into a single thread and may be in the form of a cap spinning device.

To cause evaporation of the volatile solvent contained in the spinning solution extruded through the orifices of the jet 6, a heated gas such as air, nitrogen, carbon dioxide or hydrogen is caused to flow up through the spinning unit. The 130 gas may be heated prior to entry in the base of the spinning unit or the gas may be heated by coils in the base of the spinning unit or by steam coils 10 placed along the walls 1 thereof. If desired, two or all three of these methods of heating the evaporative gas may also be employed. The evaporative gas may be forced into the base of the spinning unit or it may be drawn up through the same by suction supplied to the exhaust pipe 11 which is preferably supplied with 140 a perforated cap 12.

In the form of my invention shown in Figure 1, the spinning solution pump 3 and connecting pipe 4 are contained in a chamber 15 formed by the partition 16, while the candle filter 5 is placed 145 in a tightly fitting tube 17 surrounded by the chamber 18 formed by the partition 19. The chambers 15 and 18 may be common to all of the spinning units of the cabinet or these chambers may be interconnected with those of the other 150

spinning units of the cabinet in those cases where more than one spinning unit are employed in a cabinet. Any suitable heating medium as above described may be circulated in the chambers 15 and 18 and the temperatures of these cabinets may be the same or they may be different. If they are different, the temperature of the chamber 18 should preferably be higher than that of the chamber 15. In any event, the temperature of the 10 heating media and the amount of surface of the pump 3, pipe 4, and candle 5 should be such that when the spinning solution leaves the spinning jet 6, it has a temperature that is substantially in equilibrium with the temperature of the 15 drying evaporative atmosphere.

In the form shown in Figure 2, no candle filter is used, the spinning solution being completely filtered prior to its being introduced to the pump 3. In this case a pipe 20 that is screw-threaded 20 at each end replaces the candle 5 of Figure 1, and the spinning solution is caused to attain the desired temperature in the tube 20. The construction of the other parts of the device shown in Figure 2 is otherwise the same as that shown in 25 Figure 1.

Often when the boiling point of the solvent employed in the spinning solution is appreciably above room temperature, I prefer not to heat the spinning solution while in the pumps, since this 30 may cause mechanical difficulty. In those cases I use the device shown in Figure 3 wherein the pump 3 is outside of the spinning unit and the spinning solution is previously filtered and then heated. For the heating, I may employ the chamber 25 35 formed by the partition 26 and the spinning solution passes from the pump 3, pipe 4 to the screw-threaded pipe 27 contained in the chamber 25, which is provided with any suitable heating media as above described.

40 As described in my copending application No. 333,844 filed herewith, it is desirable to have the cross sectional area of the space wherein the solvent is evaporated from the filaments restricted. In Figure 4 there is shown means for 45 combining the advantages of heating the spinning solution prior to extrusion through the spinneret with the advantages of employing a restricted evaporating space. In this figure the means for preheating the spinning solution is precisely that 50 as shown in Figure 1, but the evaporative space is restricted by means of the partitions 30 so that the space through which the heated evaporative atmosphere flows is greatly reduced.

In all of the forms shown on the drawing it 55 will be seen that the pipe 11 for exhausting the heated evaporative gas passes through the heating chambers 18 or 25. This arrangement provides auxiliary means for heating the heating medium in these chambers, since the exhaust 60 gases passing through this pipe 11 are at a substantially uniform elevated temperature.

As an illustration of a mode of carrying out 65 my invention the following is given. A spinning solution containing 25 parts by weight of an acetone soluble cellulose acetate is dissolved in 75 parts by weight of a solvent mixture containing 95% of acetone and 5% of water. This solution is fed by the pipe 2, pump 3, pipe 4 and candle 5 to the spinning jet 6. The tem-

perature of the heating media contained in the chambers 15 and 18 is such that the temperature of the spinning solution just prior to the time it issues from the jet is approximately 55° C. Air is drawn through the spinning unit 1 and the temperature of the heating coils 10 is such that the temperature of the air is maintained at approximately 60° C. The spinning solution is fed at such rate and is drawn by the rotating roller 9 at such rate that a yarn of 150 80 denier containing 40 filaments is spun at the rate of 100 meters per minute. The yarn so produced has a bright lustre and has a substantially uniform cross section. If the temperature of the heating media contained in the chambers 15 and 18 is reduced so that the temperature of the spinning solution is reduced from 55° C., as above described, to 50° C., the yarn produced has a duller lustre and has a much flatter cross 85 section.

It is to be understood that the foregoing detailed description is given merely by way of illustration and that many variations may be made therein without departing from the spirit of my invention.

Having described my invention what I claim and desire to secure by Letters Patent is:

1. In a device for dry spinning of artificial filaments from solutions of organic derivatives of cellulose in a volatile solvent, the combination of a spinning unit through which a heating gas is adapted to flow, a spinning jet in said spinning unit, a pump and means for feeding the spinning solution to said jet and means for heating said pump and said feeding means.

2. In a device for dry spinning of artificial filaments from solutions of organic derivatives of cellulose in a volatile solvent, the combination of a spinning unit through which a heating gas is adapted to flow, a spinning jet in said spinning unit, a heating chamber superposed upon said spinning unit, a pipe for leading the heated gas from the spinning unit through the heating chamber and means contained in said chamber for feeding spinning solution to said 115 spinning jet.

3. In a device for dry spinning of artificial filaments from solutions of organic derivatives of cellulose in a volatile solvent, the combination of a spinning unit through which a heating gas 120 is adapted to flow, a spinning jet in said spinning unit, a heating chamber containing a heated liquid superposed upon said spinning unit, a pipe for leading the heated gas from the spinning unit through the heating chamber and means within 125 said heating chamber for feeding spinning solution to said spinning jet.

4. Method of forming artificial filaments comprising forcing a heated solution of an organic derivative of cellulose in 95% acetone through 135 a passage surrounded by a relatively large volume of a heating medium whereby the solution is heated and maintained at a uniform temperature of substantially 55° C. and then extruding the same through the orifices of a spinneret into a 140 drying evaporative atmosphere of air drawn through the cell.

WILLIAM WHITEHEAD.
